CONCEALED HINGE

Joseph Soss, Roselle, N. J.

Application February 20, 1936, Serial No. 64,830

14 Claims. (Cl. 16—166)

This invention relates to concealed hinges and particularly to hinges of this class which are commonly known as hinges of the hook arm type; and the object of the invention is to provide a hinge of the class specified, the hook arm of which consists of main and supplemental parts which are collectively and independently movable with respect to the butt housing, and whereby the supplemental part will permit a greater 10 swinging movement of the door by reason of the independent movement of said part with respect to the main part; a further object being to provide an independent mounting of the supplemental hook arm part in connection with the butt 15 housing or the spaced bearing plates thereof and to guide said mounting in the different movements of the supplemental part; a further object being to provide means for detachably coupling the supplemental hook arm part to the main hook arm part to provide quick and simple attachment and detachment of the door with respect to a door frame; a still further object being to provide a hinge of the class described, the 20 separate parts of which are composed of sheet metal whereby the hinge may be constructed economically and thereby sold at a reasonable price; a still further object being to provide the supplemental hook arm part with a hood portion which partially conceals both main and supplemental hook arm parts, and at the same time, 25 produces a neat and finished appearance to the hook arm structure of the hinge; and with these and other objects in view, the invention consists in a hinge of the class and for the purpose specified, which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan view of a hinge made according to my invention showing the same in closed position and partially indicating the supports therefor in dot and dash lines.

Fig. 2 is a transverse sectional view of the hinge shown in Fig. 1 in a partially open position.

Fig. 3 is a transverse sectional view substantially on the line 3—3 of Fig. 4 showing the hinge in a fully open position; and,

Fig. 4 is a face view of the hinge as shown in

Fig. 3 with parts of the construction broken away.

The hinge forming the subject matter of my invention is of the concealed hook arm type and consists of a housing butt part 5 and a swinging 5 hook arm butt part 6 consisting, in the construction shown, of a main arm 7 and a supplemental arm 8. The housing butt part 5 in the construction shown consists of a facing plate 9 of sheet metal which has an angularly extending flange 10 at one side thereof.

Centrally of the plate is a large opening 11, upper and lower walls of which are provided with notches or cut-outs 12 adjacent the flanged side edge of said plate. Welded or otherwise secured 15 to the inner surface of the plate 9 are substantially L-shaped upper and lower bearing plates 13, each consisting of a part 14 arranged directly upon the plate 9 and secured thereto and an angularly extending as well as offset plate 15. Opposed surfaces of the plates 15 are arranged in alignment with the upper and lower edges of the apertures 11 as clearly indicated in Fig. 4 of the drawing.

In Fig. 1 of the drawing, I have indicated in 25 dot and dash lines at 16 the door frame in connection with which the butt 5 is mounted. At 17, I have indicated in dot and dash lines a part of the door in connection with which the supplemental arm 8 of the butt part 6 is mounted. It will appear upon a consideration of Fig. 1 of the drawing that the bearing plates 15 extend into the stationary support 16. Apertures are formed in the offset corner 15a of said plates to receive a pintle pin 18 employed for pivotally mounting 30 the main arm part 7 in connection with the butt housing. Said part 7 is formed from a strip or sheet of metal, one end of which is curled to form a substantially cylindrical bearing 20 in connection with which a headed pintle pin 21 is detachably mounted.

The supplemental arm 8 is also formed from sheet metal and the end portion 22 of this arm is substantially of the same width as the corresponding portion of the arm 7 but of different 45 contour and the part 22 terminates at its free end in a curved knuckle 23 in which is secured a pin 24 which projects beyond the upper and lower surfaces of the knuckle 23 to extend into and through bearing plates 15 or guide channels or 50 apertures 25 formed therein. The inner end portion 25a of the apertures 25 are on an arc, the axis of which constitutes the center of the pin 18, whereas the end portions 25b of the apertures 25 are on an arc, the axis of which is the center 55

of the pin 24 when the latter is in the position assumed when the main arm 7 is in its fully open position so as to permit the pin 24 to swing on the axis 21 in the movement of the supplemental arm 8 independent of the arm 7. From a point beyond the corner 27 of said arm, the angularly extending part 28 of the arm 8 is of greater width than the end portion 22, and also of greater width than the arm 7 as may be seen at the right of Fig. 4 of the drawing. The free end of said part 28 is cut out centrally as indicated at 29 to receive the cylindrical bearing 20 of the part 7.

At opposite sides of the cut-out 29, or in other words, above and below said cut-out, the ends of the part 28 are curled to form pintle bearings 28 arranged directly above and below the bearing 20 and through which the headed pin 21 passes so as to provide the hinge mounting between the main and supplemental arms 7 and 8 to provide the independent swinging movement of the supplemental arm 8 from the position shown in Fig. 2 to the position shown in Fig. 3 and vice versa in the opening and closing movement of the hinge.

I preferably employ anti-frictional sleeves 30 on the protruding ends of the pin 24 to relieve the frictional engagement upon the surfaces of the apertures 25. It will be understood that the outer end portion of the ends 25b of said apertures extend through the bearing plates and register with the notches or recesses 12 in the upper and lower walls of the plate 9 so that when the pin 21 is removed, the pin 24 including the bearings 30 thereon may be drawn outwardly through the notches 12. It will appear, however, that when the parts are assembled, the side walls 12a of the notches 12 act as stops limiting further outward movement of the arm 8 when the arms 7 and 8 are coupled together by the pins 21.

I also preferably employ a shell or hood portion 31 for concealing or partially concealing the arms 7 and 8 as well as to reinforce and strengthen the arm structure the hood portion 31 where it abuts the arm 8 being welded or otherwise secured thereto. This hood consists of a curved wall portion 32 which is of a contour different from that of the part 22 upon which it is arranged. This wall terminates at one end adjacent the corner 27 and at its other end in a part 33 which extends around the bearing or knuckle 23 as clearly seen in Fig. 2 of the drawing. The upper and lower edges of the hood 31 are extended to form top and bottom cover plates 34 which are of the same contour. These plates extend over the upper and lower edges of the arms 7 and 8 as clearly seen in Figs. 1 and 3 of the drawing. The pin 24 passes through said top and bottom plates 34 where they are arranged outwardly of the upper and lower surfaces of the knuckle 23. The end portion 34a of the plates 34 are arranged angularly to the inner surfaces of the part 28 of the arm 8 and terminate short of the bearings 29 as may be seen in Fig. 3 of the drawing.

The design or curvature of the hook arms may be varied to suit the different installation requirements, the butt housing being also fashioned to suit these requirements and also to give the desired throw or swing of the door. This is also true of the form and guidance of the supplemental hook arm which is movable independently of the main arm to give the added door throw. The disclosure in the accompanying drawing is

only illustrative of one method of carrying my invention into effect.

In the accompanying drawing, when the butt parts 5 and 6 are in closed position, the arms 7 and 8 are in their substantially nested position one within the other and within the hood 31. The pin 24 is disposed at the inner end of the parts 25a of the apertures 25. In the operation of opening the door, the arms 7 and 8 will maintain their relative position with respect to each other until the parts reach the position shown in Fig. 2 of the drawing, in which position, the outward movement of the arm 7 is checked. In continuing to swing the door or move the same into open position, the arm 8 swings upon the pintle pin 21 and the pin 24 including the bearings 30 thereon are guided through the parts 25b of the apertures 25 from the position shown in Fig. 2 to that shown in Fig. 3. In reversing the above operation, or, in other words, in closing the door, the arm 8 first moves from the position shown in Fig. 3 to the position shown in Fig. 2, and then, both arms 7 and 8 swing inwardly to return to the position shown in Fig. 1.

The plate portion 26 of the arm 8 of the hinge will be fashioned to facilitate attachment to a door by screws, riveting, welding or otherwise. By reason of the detachable pintle 21, this attachment to the door may be more or less permanent because of the detachable mounting of the door including the arm 8 with respect to the arm 7 and the butt 5. The plate 9 including the parts 14 of the L-shaped bearing plates 13 may be fashioned in any desired manner for attachment to the door frame by screws, bolts or the like.

My improved hinge is designed primarily for use as a hinge for motor vehicles but will have its usefulness in any other type of door hanging, especially where the use of concealed hinges is desirable. By constructing the several parts of the hinge from sheet metal, the same may be produced at a very nominal cost and at the same time, a strong and durable hinge is provided.

Having fully described my invention, what I claim as new and desire to secure by Letters Patent, is:

1. A concealed hinge of the class described comprising a housing butt part and a hook arm butt part, said arm being pivotally mounted within the housing and adapted to swing inwardly and outwardly with respect thereto on said pivot, said arm including a supplemental arm part movable with and independently of the first named arm, means for guiding the supplemental arm in the butt housing in its respective movements, the free end portions of the first named and supplemental arms having interengaging pintle bearings with a common pintle mounted in said bearings to provide relative hinge movement between said arms, and a sheet metal hood mounted upon the supplemental arm and including top and bottom plates concealing the first and second named arms.

2. A concealed hinge of the class described, one butt of which comprises top and bottom bearing plates, the other butt of the hinge comprising two arms pivoted together at one end portion thereof, the other end of one of said arms having a fixed pivot in said bearing plates, and the corresponding end of the other arm and said bearing plates having interengaging means for guiding said end of the arm in two distinct arcuate paths in the swinging movement of said arms collectively with respect to the first named

butt and during independent movement of the second named arm with respect to said first named arm.

3. A concealed hinge of the class described, one butt of which comprises top and bottom bearing plates, the other butt of the hinge comprising two arms pivoted together at one end portion thereof, the other end of one of said arms having a fixed pivot in said bearing plates, the corresponding end of the other arm and said bearing plates having interengaging means for guiding said end of the arm in two distinct arcuate paths in the swinging movement of said arms collectively with respect to the first named butt and during independent movement of the second named arm with respect to said first named arm, the interengaging means between the second named arm and bearing plates comprising projecting members on said arm, and channels in said bearing plates in which said projecting members operate.

4. A concealed hinge of the class described, one butt of which comprises top and bottom bearing plates, the other butt of the hinge comprising two arms pivoted together at one end portion thereof, the other end of one of said arms having a fixed pivot in said bearing plates, the corresponding end of the other arm and said bearing plates having interengaging means for guiding said end of the arm in two distinct arcuate paths in the swinging movement of said arms collectively with respect to the first named butt and during independent movement of the second named arm with respect to said first named arm, the interengaging means between the second named arm and bearing plates comprising projecting members on said arm, channels in said bearing plates in which said projecting members operate, and the second named arm having a curved hood portion including top and bottom walls arranged over upper and lower edges of the first and second named arms.

5. A concealed hinge of the class described, one butt of which comprises top and bottom bearing plates, the other butt of the hinge comprising two arms, a pivot coupling said arms at one end portion thereof, the other end of one of said arms having a fixed pivot in said bearing plates, the corresponding end of the other arm and said bearing plates having interengaging means for guiding said end of the arm in two distinct arcuate paths in the swinging movement of said arms collectively with respect to the first named butt and during independent movement of the second named arm with respect to said first named arm, the interengaging means between the second named arm and bearing plates comprising projecting members on said arm, channels in said bearing plates in which said projecting members operate, the second named arm having a curved hood portion including top and bottom walls arranged over upper and lower edges of the first and second named arms, and means involving the first named pivot and first named means for detachably mounting the second named arm in connection with said first named arm and said first named butt.

6. In a concealed hinge of the class described, a butt housing in connection with which two hinge members are mounted for independent movement, said housing comprising a front plate having inwardly extending and spaced bearing plates arranged in alinement with an opening

formed in said front plate, said bearing plates having an aperture for receiving a fixed pintle for one of said hinge members, each of said bearing plates having two differently arced intercommunicating channels for guiding the other of said hinge members in its movement relatively to said housing and one of said channels having its arc center common with the axis of said pintle, whereby both of said members move as a unit in swinging through said arc. 10

7. In a concealed hinge of the class described, a butt housing in connection with which two hinged members are mounted for independent movement, said housing comprising a front plate having inwardly extending and spaced bearing plates arranged in alinement with an opening formed in said front plate, said bearing plates having an aperture for receiving a fixed pintle for one of said hinge members, each of said bearing plates having two differently arced intercommunicating channels for guiding the other of said hinge members in its movement relatively to said housing, and the arc or curvature of one channel in each plate being arranged arcuately with respect to the axis of said pintle 20 apertures. 25

8. In a concealed hinge of the class described, one of the butts of said hinge comprising spaced bearing plates, the other butt consisting of two hook-shaped arms arranged one outwardly of the other, means for mounting one end of the inner arm on a fixed pivot in said plates, the other end of said arms having interengaging knuckles arranged on a common pintle, and means for guiding the other end of the outer arm in said plates arcuately with respect to the pivot of the first named arm in said plates as well as arcuately with respect to the pintle coupling between both of said arms. 30

9. A concealed hinge of the class described comprising a butt housing and two hook arm butt parts, one end of each of said parts having an independent mounting in the butt housing, the other end of said parts being pivotally coupled together, both parts comprising a substantially straight outer portion and a curved inner portion with the walls of said portions in substantially parallel relation with respect to each other when said parts are in closed position. 40

10. A concealed hinge of the class described comprising a butt housing and two hook arm butt parts, one end of each of said parts having an independent mounting in the butt housing, the other end of said parts being pivotally coupled together, both parts comprising a substantially straight outer portion and a curved inner portion with the walls of said portions in substantially parallel relation with respect to each other when said parts are in closed position, and one of said parts having top and bottom walls arranged over upper and lower edges of the other part. 50

11. A concealed hinge of the class described comprising a butt housing and two hook arm butt parts, one end of each of said parts having an independent mounting in the butt housing, the other end of said parts being pivotally coupled together, both parts comprising a substantially straight outer portion and a curved inner portion with the walls of said portions in substantially parallel relation with respect to each other when said parts are in closed position, and one of said parts having a sheet metal hood portion including top and bottom walls overlying upper and lower edges of both of said parts. 60

12. A concealed hinge of the class described comprising a housing butt part and a hook arm butt part, said arm being pivotally mounted within the housing and adapted to swing inwardly and outwardly with respect thereto on said pivot, said arm including a supplemental hook-shaped arm part of substantially the same form as the first named arm and normally covering said first named arm and movable with and independently 10 of said first named arm, and means for guiding the supplemental arm in the butt housing in its respective movements.

13. A concealed hinge of the class described comprising a housing butt part and a hook arm butt part, said arm being pivotally mounted within the housing and adapted to swing inwardly and outwardly with respect thereto on said pivot, said arm including a supplemental hook-shaped arm part of substantially the same form as the first named arm and normally covering said first 20 named arm and movable with and independently of said first named arm, means for guiding the supplemental arm in the butt housing in its respective movements, and the free end portions of the first named and supplemental arms terminating 25 in interengaging pintle bearings with a

common pintle mounted in said bearings to provide relative hinge movement between said arms.

14. A concealed hinge of the class described comprising a housing butt part and a hook arm butt part, said arm being pivotally mounted within the housing and adapted to swing inwardly and outwardly with respect thereto on said pivot, said arm including a supplemental hook-shaped arm part of substantially the same form as the first named arm and normally covering said first 10 named arm and movable with and independently of said first named arm, means for guiding the supplemental arm in the butt housing in its respective movements, the free end portions of the first named and supplemental arms terminating 15 in interengaging pintle bearings with a common pintle mounted in said bearings to provide relative hinge movement between said arms, and the means for guiding the supplemental arm in its movement with respect to said housing comprising a pin on the supplemental arm extending beyond the upper and lower surfaces thereof and operating in curved channels in the top and bottom of said housing, said channels having two different axes. 20

JOSEPH SOSS. 25
